August M. Augensen,

UNITED STATES PATENT OFFICE.

AUGUST M. AUGENSEN, OF MAYWOOD, ILLINOIS, ASSIGNOR TO AMERICAN CAN COMPANY, OF NEW YORK, N. Y., A CORPORATION OF NEW JERSEY.

DISTRIBUTING MECHANISM FOR CAN-CONVEYERS.

1,236,391.

Specification of Letters Patent. Patented Aug. 14, 1917.

Original application filed April 18, 1914, Serial No. 832,696. Divided and this application filed April 22, 1915. Serial No. 22,999.

To all whom it may concern:

Be it known that I, AUGUST M. AUGENSEN, a citizen of the United States, residing in Maywood, in the county of Cook and State 5 of Illinois, have invented a new and useful Improvement in Distributing Mechanism for Can-Conveyers, of which the following is a specification.

This invention relates to improvements in 10 can conveyers and distributers and is a division of my co-pending application Serial No. 832,696, filed April 18, 1914, for can conveyers and distributers.

One object of the invention is to provide 15 simplified mechanism for distributing a single line of rapidly moving cans into a plurality of lines and directing the cans thus separated to a plurality of closing machines.

Another object of the invention is to provide 20 mechanism so arranged that a minimum amount of floor space is utilized for distributing filled cans as they come from a filling machine to a plurality of closing machines and then transferring the closed filled 25 cans as they come from the closing machines to a conveyer for transferring them to the packing room or storing room.

The invention furthermore consists in the 30 improvements in the parts and devices and in the novel combinations of the parts and devices herein shown, described or claimed.

In canning factories it has been found 35 that a battery of can closing machines, each running at a slow speed, gives better results than a single can closing machine running at a high speed, since greater opportunity is given for inspection and spilling is minimized. It has also been found that the filling machines now commonly employed to 40 place measured quantities of the contents into the open cans, operate generally at a higher speed than closing machines so that when a filling machine is running at full speed, it is necessary to employ a battery 45 of can closing machines to take the entire product therefrom. Furthermore, a packer in the height of the season is sometimes required to run his entire plant at maximum capacity day and night and at such times 50 it is essential that auxiliary or emergency closing machines be provided to take the place of any closing machine which may happen to break down or is stopped for any reason. It is also an important considera-

tion in canning factories to use a minimum 55 amount of floor space to be occupied by the conveyers for transporting the cans to the closing machines and from the latter to the labeling machines or to the packing room. I have provided an arrangement which takes 60 into account all of the above mentioned factors and the same consists in a distributer so arranged that the cans as they come from a filling machine at high speed are distributed successively, positively and in rotation to a battery of closing machines, the distributer being so arranged that in case any one of the battery of closing machines 65 breaks down, the cans may be switched to an emergency or auxiliary closing machine 70 without stopping the feeding of the cans. A receiving belt is also provided for receiving and conveying the closed filled cans after the same have been operated upon by the closing machines, said conveyer being 75 mounted upon the same framework as the distributing arrangement and preferably below the latter, thus minimizing the amount of floor space required for the entire apparatus.

In the drawing forming a part of this specification, Figure 1 is a top plan view of one form of apparatus embodying my improvements, the closing machines being indicated diagrammatically. Fig. 2 is a side 85 elevation of the distributing mechanism and receiving and conveying belt, parts being broken away in order to prevent crowding of the drawing. Fig. 3 is an enlarged plan view showing the entrance end of the distributing mechanism. Fig. 4 is a transverse, vertical section showing the framework on which the conveying and distributing belts are mounted and also the chute from a closing machine for the closed filled cans, the 90 section being taken substantially on the line 4-4 of Fig. 1, and Fig. 5 is a detail perspective view of one of the switches or deflecting fingers employed with my mechanism.

In said drawing, the parts are shown as mounted on a framework having uprights 10, 10; horizontally arranged angles 11 at the top thereof and other angles 12, 12 below the angles 11, 11, said angles 11, 11 and 12, 12 forming horizontal supports or guideways for the upper webs of two endless belts or conveyers 13 and 14, both of which travel

in the same direction as indicated by the arrows in Fig. 2. The lower webs of the conveyers travel over a plurality of rollers 15, 15 suitably supported, as shown. The 5 conveyers are supported on pulleys 16, 16 at the ends of the framework which are rotated by suitable means, such as the worm gear drive 17, shaft 18, sprocket gear 19, sprocket chain 20 and sprocket gear 21. 10 Above the conveyer 13 and suitably secured to the framework is a plurality of bridges 22 to which are secured a plurality of longitudinally extending bars 23, 23 forming three guideways or passages 24, 25 and 26, 15 see Fig. 1. A plurality of gates 27 are arranged as shown in Fig. 1 so that the cans as they come down the various passageways 24, 25 and 26 may be deflected to any one of the can closing machines A, B, C or D, 20 it being understood that during normal operation of the parts, only the machines A, B and C are utilized. However, in case of breakdown of either of the machines A, B and C, the gates will be so arranged that 25 the cans will be fed to only two of the machines on the one side of the distributor and the remaining cans to the machine D.

The filled cans are brought from the filling machine (not shown) onto the conveyer 30 13 and along the single passageway 28. This passageway is formed by two bars 29, 29 bent and arranged as shown in Fig. 3. Extending into the space between the bars 29, 29 and supported on an adjustable 35 bracket 30 is a rotatable, positioning or displacing plate 31, the latter having an irregularly shaped periphery preferably of the form shown most clearly in Fig. 3. The periphery comprises two diametrically disposed concave surfaces 32; two diametrically disposed reversely curved surfaces 33; and two diametrically disposed surfaces 34. As the cans are moved past said member 31 40 by the conveyer 13, they engage the said member and rotate it, and thus cans which strike the surfaces referenced 33 and 34 are displaced away from their general line of travel toward the passageway 35 and cans which engage in the concave portions 32, 45 32, are swung from the general line of travel in the general direction of the passageway 36. In this way, it will be seen that two cans are displaced to one side of the general line of travel and one can to the 50 other side out of each three cans coming along the passageway 28. After the cans pass by the rotatable member 31, they engage a triangular shaped, spring-controlled pivoted deflecting finger or switch 37 which 55 is mounted on a rounded end 38 of a bar secured to the end bridge 22. As will be understood, the cans which are transmitted down the passageway 36 will either be deflected to the machine referenced A or will 60 65 continue along the passageway 26 to either

of the other machines depending upon the positions of the various gates 27. In order to distribute the cans which are transmitted through the passageway 35, a second rotatable positioning or displacing member 39 70 is employed, the principle upon which it operates being similar to that of the plate 31 except that the plate 39 has only four faces instead of six, the concave faces 40, 40 guiding the cans to the passageway 24 75 and the faces 41, 41 displacing the cans so that they pass to the intermediate passageway 25. Another deflecting finger or switch 37 is employed and the member on which it is mounted is made adjustable, as shown by 80 the bolt and slot arrangement 42. From the preceding description it will be seen that the cans are distributed successively and in rotation in equal numbers to the three passageways 24, 25 and 26, and it will be obvious that my invention is not limited to a distributing arrangement employing merely 85 three passageways.

At each of the closing machines, the cans are received on a table 43, after which they 90 are passed through the machine and have an end or cover seamed thereto. After the cans pass the seaming mechanism they are ejected from the machine onto an inclined, curved, channel-shaped chute 44, see Fig. 1, and 95 slide down the latter under the influence of gravity. The chutes 44 are so arranged that they direct the closed filled cans onto the conveyer 14 and the cans are conveyed by the latter to the left hand end of the apparatus, as viewed in Fig. 2 and transferred from the conveyer 14 to a lifting conveyer 45. By arranging the conveyer 14 beneath the conveyer 13, a minimum amount of floor space is required and both conveyers are 100 105 easily accessible.

Although I have herein shown and described what I now consider the preferred embodiment of my improvements, yet it will be understood that various changes and modifications may be made without departing from the spirit of the invention and all such changes and modifications are contemplated as come within the scope of the 110 claims appended hereto.

I claim:

1. In an apparatus of the character described, in combination: a framework having an endless conveyer mounted thereon which is adapted to convey articles thereon in a plurality of parallel series of successive articles, and means for distributing articles from a single series fed to said conveyer and for distributing them in rotation to the different series of said plurality of series, 120 said means including a rotatable positioning member and a pivotally mounted deflecting finger adjacent said member and to the rear thereof.

2. In an apparatus of the character de- 130

scribed, in combination: a framework having an endless conveyer mounted thereon, a plurality of guideways above said conveyer, and means for distributing articles from a single guideway in rotation to said plurality of guideways, said means including a rotatable positioning member and a pivotally mounted deflecting finger adjacent said member and to the rear thereof, substantially as specified.

3. An apparatus of the character described comprising, in combination: a framework having an endless conveyer mounted thereon, a plurality of guideways above said conveyer, a single guideway above said conveyer at one end thereof and adjacent the entrance ends of the plurality of guideways, and means for distributing the articles in rotation from the single guideway to the plurality of guideways, said means including a member for displacing the articles

from their line of travel as they come from the single guideway and a spring-controlled pivotally mounted deflecting finger, substantially as specified.

4. In a distributing conveyer, in combination: an endless conveyer for the support of articles to be distributed: a plurality of parallel guideways above said conveyer; automatic means for unequally distributing articles one toward one of said guideways and several toward several of said guideways; alternately; and means for distributing articles to each of said last mentioned several guideways.

Signed in the presence of two subscribing witnesses.

AUGUST M. AUGENSEN.
